CLAIM

The ornamental design for a processing instrument as shown and described.

DESCRIPTION

FIG. 1 is a front perspective view of a processing instrument showing our new design containing symbolic break lines conveying that the appearance of any portion of the processing instrument between the symbolic break lines forms no part of the claimed design;

FIG. 2 is a front view of the processing instrument;

FIG. 3 is a rear view of the processing instrument;

FIG. 4 is a right side view of the processing instrument;

FIG. 5 is a left side view of the processing instrument;

FIG. 6 is a top view of the processing instrument; and,

FIG. 7 is a bottom view of the processing instrument. The dashed lines in FIGS. 1-7 indicate unclaimed portions of the disclosed processing instrument.

1 Claim, 7 Drawing Sheets
